UNITED STATES PATENT OFFICE.

OSKAR TAUSSIG, OF VIENNA, AUSTRIA.

CRANE OR SIMILAR LIFTING DEVICE.

1,327,181.

Specification of Letters Patent.

Patented Jan. 6, 1920.

Application filed February 12, 1915. Serial No. 7,670.

To all whom it may concern:

Be it known that I, OSKAR TAUSSIG, mech. engineer, subject of the Emperor of Austria, residing at Vienna, XX. Dresdnerstrasse 49, 5 in the county of Lower Austria and State of Austria, have invented certain new and useful Improvements in Cranes or Similar Lifting Devices; and I do hereby declare the following to be a full, clear, and exact 10 description of the invention, such as will enable others skilled in the art to which it appertains to make and use the same.

My invention relates to cranes or similar lifting devices and has for its object the 15 provision of an auxiliary device to secure slow and soft lifting of heavy loads, especially at the beginning or during the first stage of lifting; so designed, however, that after the load has once been lifted for a 20 relatively small height, further lifting of the load may be carried out more rapidly and in the usual manner.

With previous cranes or the like provided to effect a soft or easy lifting initially, as 25 in foundries or in mounting or erection plants, such gentle lifting has been produced by a proportional throttling of the efficiency of the driving motor, a procedure which obviously has been accompanied by 30 many inconveniences.

According to the present invention the initial elevation of the load is effected by an auxiliary source of power which functions prior to the main source of power, at 35 any desired point of the entire lifting apparatus, as at the point of application of the load, at the suspension point of the hook, at the place of anchoring the end of the rope or of the chain, at the bearings of the 40 rope or chain drum or wheel, or suitably elsewhere.

Obviously it will also be possible to arrange the main source of power itself so that it will assist in the first slow and soft lifting of the load. For example, there may be provided a connecting gear, engaging with the driving gear of the main lifting apparatus, and, if desired, transmitting rotation from one gear to a slower one; and, 50 in addition, means operable to throw the connection gear into and out of connection with the main driving gear.

The principle of the invention may be structurally carried into effect in many different ways, some of which are illustrated 55 in the annexed sheets of drawings, in which

Figures 1 and 2, in vertical section and in plan respectively, show one embodiment of the invention as applied to the crane-carriage;

60

Fig. 3, similar to Fig. 1, shows a modification;

Figs. 4 and 5, in elevation and in plan respectively, show another modification;

Figs. 6 and 7, in front and side elevations 65 respectively, show an embodiment as combined with the lifting hook.

Fig. 8 is a view showing certain of the parts of Fig. 3, illustrating another modification; and

70

Fig. 9 is a view showing certain of the parts of Fig. 1, illustrating still another modification.

In Figs. 1 and 2 there is represented a crane-carriage of usual construction. To 75 fully understand the drawing, it is sufficient to state that the carriage consists of a frame formed by channel irons 1, 2, 3 and 4, which frame carries wheels 5, 6, 7 and 8 resting upon suitable track rails not shown in the 80 drawing. The wheels 5 and 7 are keyed on a shaft 9 and the wheels 6 and 8 are keyed on a shaft 10. The carriage travels on its track rails, the drive being from a rope- or chain-pulley 11, through pinion 12 and gear 13, the former fast on the pulley shaft and the latter fast on shaft 10. The frame is also provided with a shaft 14 which may be driven through a rope or chain-pulley 15, the shaft 14 in its turn driving a shaft 20 85 90 by means of pinion 16, gear 17, pinion 18 and gear 19. A sprocket wheel 21 is keyed on the shaft 20. Over this sprocket wheel 21 is passed a chain 22, which then passes around a movable sprocket wheel 23 and 95 finally leads to a point of attachment on the carriage.

From the axis of the movable sprocket wheel 23 are pendant side shields 25, suspending a hook 26. As the sprocket wheel 100 21 is driven in one direction or the other, the movable sprocket wheel 23 and the hook 26 are lifted or lowered.

According to the present invention the point 27 where the end of the chain is attached to the carriage, is movable contrary to the ordinary fixed arrangement. Here such connection is not anywhere on the body of the carriage, but is located upon the strap 28 of an eccentric 29. As a result, sprocket 105 wheel 21 may remain stationary, and yet a slight rotation of eccentric 29 will displace

110

strap 28 so that hook 26 may be gently and gradually raised, without necessitating any other operation preparatory to using the main driving apparatus either later or simultaneously. In order to require but small power to thus rotate the eccentric 29, the shaft 30 upon which the eccentric is keyed has fast thereon a worm-wheel 31, in mesh with a worm 32 rotating with a worm-wheel 33, the latter worm-wheel meshing with a worm 34 driven by a small motor 35.

The carriage represented in Fig. 3 shows a similar construction as that before described, the only difference being that the point of attachment 36 of the chain 37 is on a hanger 38, pivotally suspended from one arm 39 of a bell crank lever, the other arm 40 of which is operated by a rope 41 or the like. It is obvious, that by means of this device the point of attachment 36 of the chain 37 may be lifted and lowered, whereby initial lifting of the load suspended from the hook 42 may be effected softly by means of a pull exerted upon the rope 41 and further lifting of the load may be effected in the usual manner by means of a sprocket wheel 43.

In the modification shown in Figs. 4 and 5 the principle of the invention as explained in the preamble of this specification is applied in the following manner. Shaft 44, corresponding to the shaft 20 of Figs. 1 and 2, has fixed thereon a main chain-driving sprocket-wheel 45, which may not only be driven by a main driving apparatus similar to that of Figs. 1 and 2, but also and independently by an auxiliary or "gentle" driving apparatus. As to this main driving apparatus of Figs. 4 and 5, of course the gear 44' corresponds to the gear 19 of Figs. 1 and 2. The auxiliary driving apparatus includes the pinions 46 and 47, the idler gear therebetween as shown best in Fig. 4, and another or other suitable gears not illustrated. The pinion 46 or 47 will rotate with the armature-shaft of a small auxiliary motor 48, and the other pinion will mesh directly with the unillustrated gear just mentioned.

As a matter of course suitable clutches will be provided so that alternately or as desired, the shaft 44 will be driven by means of either the gear 44' or the motor 48. Hence the first stage of elevation of the load may be effected in a soft or gentle manner by means of the motor 48 (the gear ratios having been conveniently determined), and then, after changing the clutch connection, further elevation of the load may be effected by the usual apparatus.

60 Figs. 6 and 7 show another application of the fundamental idea of the invention.

In this case the usual hook 49 carries a casing including two shields 51 by means of a yoke shaped bolt 50. Within the casing is 65 located an eccentric 52, the strap 53 of which

carries the "load"-hook 54. Upon the axis of the eccentric is keyed a worm wheel 55, meshing with a worm 56 to be rotated by an auxiliary motor 57. The motor and the worm 56 are fastened to and carried by the 70 casing. Upon rotating the worm wheel 55 by means of the auxiliary motor 57 the eccentric 52 is turned and the position of hook 54 is altered in a vertical direction; so that here also an initial slow and soft lifting of the load suspended from the hooks 50 and 54 may be effected. Thereafter, the load may be lifted further by means of the ordinary mechanism of the crane. This construction offers the advantage that it may be applied 80 to or used with the hook or with the chain of every lifting device already known and in use.

From the structures above described it will be seen how differently the principle 85 of the invention may be practically applied; and it is of course to be understood that numerous other modifications are possible to fulfil the purpose of the invention. Furthermore, even with the modifications shown 90 as modes of carrying out the invention, the structural features may be varied; for example it is very well possible to combine the point of attachment of the chain with the piston of a hydraulic or pneumatic cylinder, 95 as shown in Fig. 8, in connection with the structure of Fig. 3, where the cylinder is indicated at 60, whereby a soft lifting of the load may be produced; or lifting screws or similar means may be employed, as shown 100 in Fig. 9, in connection with the structure of Fig. 1, where a plurality of screws are shown at 61.

What I claim is:

1. In a lifting device, the combination 105 with a device for suspending the load, suspending means for said device and means for hoisting the suspending means, of auxiliary means for hoisting said device and operable at will independently of the first 110 mentioned hoisting means, one of the hoisting means including an eccentric; substantially as described.

2. In a lifting device, the combination 115 with a load engaging device and a flexible looped traction device for the load engaging device, the traction device being at the bight of its loop connected with the load engaging device, of an eccentric to which one end of the traction device is attached, means for 120 drawing in said bight to move the load engaging device, and auxiliary means for moving the eccentric on its axis; substantially as described.

3. In a lifting device, the combination 125 with means for suspending a load and winding means for the load suspending means, of a main source of power, mechanism driven by the source of power and including a traction device, an eccentric, an eccentric strap 130

operated thereby, and an auxiliary source of power for operating the eccentric, one end of the traction device being attached to the eccentric strap.

5 4. In a lifting device, the combination of a traction device, a load engaging device hoisted and lowered by operation of the traction device, an eccentric operative to vary the height of the load engaging device,
10 and means for operating the traction device

to vary the height of the load engaging device irrespective of the operation of the eccentric; substantially as described.

In testimony whereof I affix my signature, in presence of two witnesses.

OSKAR TAUSSIG.
